UNITED STATES PATENT OFFICE.

AXEL A. STROM, OF AUSTIN, ASSIGNOR TO THE STROM MANUFACTURING COMPANY, OF CHICAGO, ILLINOIS.

SLIDE-PLATE APPLIANCE FOR SPLIT SWITCHES.

SPECIFICATION forming part of Letters Patent No. 452,323, dated May 12, 1891.

Application filed November 24, 1890. Serial No. 372,437. (No model.)

To all whom it may concern:

Be it known that I, AXEL A. STROM, a citizen of the United States, residing at Austin, in the county of Cook and State of Illinois, have 5 invented a new and useful Improvement in Slide-Plate Appliances for Split Switches, of which the following is a specification.

My invention relates to an improvement on the form of appliance for permitting the main 10 rails of a railroad-switch to be braced from the slide-plates, and comprising the slide-plate with an elevated surface at the inner side of the main rail for the adjacent point rail to slide on and an abutment at the outer extremity of the plate, formed by bending it up at its extremity, for the rear end of a rail-brace to confine the brace against the outer 15 side of a main rail, and the latter, through the medium of the brace, against a shoulder on 20 the slide-plate.

The object of my improvement is to provide a stronger and more rigid construction of abutment for confining the brace than that referred to; and it is, furthermore, my object to 25 apply the said improvement to slide-plates connected together as set forth in my application for Letters Patent, Serial No. 372,438, filed concurrent herewith on the 24th day of November, 1890, for the purposes of causing 30 them to perform in addition to their function of slide-plates that of a connecting-bar for maintaining the gage of the main rails at the switch.

In the accompanying drawings, Figure 1 is 35 a view in side elevation of a slide-plate provided with my improved construction of abutment for the rail-brace, shown as confined by it against a main-rail. Fig. 2 is a perspective enlarged view of the slide-plate. Fig. 3 is a 40 perspective view showing a single connecting-bar provided at each end with my improved abutment and adapted for use as a slide-plate appliance for both point rails.

A is the slide-plate, provided on its upper

surface with an offset *r*, from which in one direction the plate is thickened to afford the raised surface *q* for a switch-rail and a depressed surface *p* to afford a seat for a main rail C and for a rail-brace B. Near the outer end of the seat *p* the plate is provided with 45 an abutment *o*, comprising a section of the metal of the plate partly severed from the latter and raised or struck up to project obliquely above the plane of the seat-surface, the abutment being formed sufficiently far 50 from the outer extremity of the seat-surface *p* to leave enough metal behind it to render the abutment rigidly resistant to the strain exerted against it from the rail C, through the interposed brace B, which the abutment confines against the rail, the latter being thus 55 also confined against the offset *r*.

By forming the switch-rail seats *q* and main-rail seats *p* on a continuous plate or bar D, as represented in Fig. 3, the device serves the additional purpose of a tie-bar for effectually holding the main rails against spreading and thereby reliably maintaining their gage at the switch, where it is of great importance that the main rails shall not spread under the 60 strain of passing trains.

What I claim as new, and desire to secure by Letters Patent, is—

1. A slide-plate having on its main-rail and rail-brace seat portion an oblique abutment 75 *o*, struck up therefrom between the extremities of the said seat portion, substantially as described.

2. A slide-plate A, having the raised switch-rail surface *q* extending from an offset *r*; and 80 the depressed main-rail and rail-brace seat *p*, and the oblique rail-brace abutment *o*, struck up from the seat portion *p* between the ends thereof, substantially as described.

AXEL A. STROM.
